FOLDED FIBROUS MATERIAL PRODUCT

Norval F. Wilson, East Alton, Ill., assignor to
 Alton Box Board Company, Alton, Ill., a corporation of Delaware

Application June 3, 1944, Serial No. 538,632

4 Claims. (Cl. 40—125)

1

The invention relates to a panel, plaque, plate or the like made from a sheet of non-metallic fibrous material such as paper, cloth or a combination of the same, a familiar example of which is cardboard used in construction of paper boxes, cartons, etc.

The main object of the invention is to provide a substantially rigid panel-like or plate-like article of material such as described which is durable and particularly is adaptable to withstand exposure to the weather and such rough usage as exposed signs, vehicle license plates, etc. are subjected.

A more specific object is to construct a panel of the type described, such as a vehicle license plate, of non-metallic fibrous sheet material having cut edges so that the cut edges entirely or substantially will be covered and not exposed.

These and other detail objects as will be apparent from the following description are attained by the structure illustrated in the accompanying drawings, in which—

Figure 1 is a plan of a blank of sheet material from which a vehicle license plate may be constructed.

Figure 2 is a front view of a completed plate.

Figure 3 is a rear view of the plate.

Figure 4 is a vertical section taken on the line 4—4 of Figure 2.

Figure 5 is a horizontal view taken on the line 5—5 of Figure 2.

Figures 6 and 8 correspond to Figure 1 but illustrate modified forms of a sheet from which a license plate may be formed.

Figures 7 and 9 are sections taken on the corresponding lines of Figures 6 and 8, respectively, after the respective plates have been completed.

The sheet illustrated in Figure 1 may be of any suitable non-metallic fibrous material, such as cloth, paper or like material in which the fibers F are laid flat with their length disposed in the plane of the sheet. Preferably, the manufacture of the material will include a pressing or ironing step which gives at least one face of the sheet a smooth finish, adapting it for a display surface. If desired, this surface may be calendered.

The sheet is die cut or otherwise trimmed to the cruciform contour indicated, and such trimming involves the shearing of the fibers at the edges of the sheet. When so trimmed, the sheet will comprise a central body portion 1, end lobes 2, a lower lobe 3 and an upper lobe 4. Fold lines for the end lobes 2 are indicated

2

at 2a, for the lower lobe 3 at 3a, and for the upper lobe 4 at 4a. Preferably, fold lines 2a are offset a short distance outwardly from the cut edges 3b of the lower lobe and 4b of the upper lobe.

To form the panel, the face of the sheet nearest the observer is coated with a suitable cement, preferably waterproof or water-repellent, such as asphaltum, rubber in solution, or a plasticized adhesive, for example a polyvinyl alcohol product. Then end lobes 2 are folded about fold lines 2a to overlie the central body portion. Lower lobe 3 is folded about fold line 3a to overlie the folded end lobes 2 and the central body portion 1, and then upper lobe 4 is folded about fold line 4a to overlie the lower lobe 3, the end lobes 2 and the central body portion 1.

The lobes will then be as indicated in Figures 2, 3, 4 and 5, and there will be formed a substantially rigid panel or plate the perimeter of which will be defined by fold edges of smooth finish sheet-surface material. The cut edges 2b of the end lobes will be covered by the lower and upper lobes. The cut edge 3c of the lower lobe will be covered by the upper lobe. The cut edges 3b and 4b of the lower and upper lobes will be exposed but will be spaced inwardly from the fold edges defining the ends of the plate. The cut edge 4c of the upper lobe will be exposed but will be spaced inwardly of the plate from the fold edge defining the top of the plate.

The plate may be provided with apertures 5 for bolts or other attaching elements. These apertures may be punched after the plate is otherwise finished, as indicated in Figures 2, 3, 4 and 5, or they may be punched in the blank of sheet material, as indicated in Figure 1. The plate may then be given one or more coatings of waterproof enamel, lacquer, varnish or liquid plastic. Such a coating is indicated at C, it being understood that the thickness is exaggerated for the purpose of illustration. Before or after this coating is applied, the plate may be imprinted with suitable indicia, that shown being recognizable as suitable for a vehicle license plate.

Figures 6 and 7 illustrate another form of the invention in which the central portion 10 and end lobes 11 correspond generally to the portions 1 and 2 described above, and the end lobes are first folded over fold lines 11a to overlie the central portion 10, but the single lobe 12 projects from one side of central portion 10, between end

lobes 11, and is of sufficient extent to be doubled first about fold line 12a and then folded on fold line 12b to overlie folded end lobes 11 and the corresponding face of central portion 10.

A license plate formed in this manner will have the same general characteristics as a plate formed as previously described, particularly in that the cut edges 11b of the end lobes will be covered by the lobe 12 and the cut edges 11c of lobes 11 and the cut edges 12c and 12d of lobe 12 and the cut edge 10c of body 1 will be spaced inwardly from edges of the plate formed by the folding over of the sheet material.

Figures 8 and 9 illustrate another form of the invention which corresponds even more closely to that shown in Figures 1-5 in having the central body portion 21, end lobes 22 and lower lobe 23 substantially the same as the corresponding parts of the blank shown in Figure 1, but the upper lobe 24 corresponds in area to the central body portion 21 and extends substantially entirely throughout the back face of the plate when the structure is completed. This makes a heavier and stiffer plate. The cut edges of the sheet material are similarly covered and spaced from the perimeter of the plate.

Each form of the invention attains the objects indicated in the introductory portion of the specification and more particularly provides a plate formed of sheet material having lobes or flaps with cut edges which are so folded that the cut edges are spaced inwardly from the perimeter of the plate and are protected from the likelihood of being bruised, scratched, distorted or affected by rough handling, by contact with extraneous objects, by water, mud, gravel, etc. which may be driven past the plate by traffic, wind, etc. Even if one of the fold edge surfaces is abraded or nicked, it is not likely to fray, as would a cut surface edge, which might tend to fray and act like a wick to absorb moisture to the interior of the sheet material causing the fibers and plies to swell and separate. The fold edges reinforce the sheet material and, even where a cut edge is exposed, as at 4c in Figures 3 and 4 or at 12c in Figure 6, there is an adjacent fold edge protecting it.

The sheet material is readily blanked and the completed panels are readily formed on the machines usually operated for producing cardboard boxes and like articles.

While the drawings and detail description disclose a specific form of the invention, namely, a vehicle license plate, the invention may be embodied in other forms, such as road signs and other signs, bulletin-boards, etc. intended to be placed outdoors, or in other installations where exposed to moisture and like destructive conditions.

The arrangement of the body portion and the lobes or flaps and their relative sizes and the order of their successive folds may be varied substantially without departing from the spirit of the invention, and the exclusive use of those modifications coming within the scope of the claims is contemplated.

What is claimed is:

1. A panel formed from a piece of fibrous sheet material comprising a display face portion, two end flap portions formed integrally with the display face portion and adapted when folded back to cooperate to cover substantially the entire back

surface of the display face portion, two side flap portions also formed integrally with the display portion and adapted when folded back to cover the back surfaces of said end flap portions, means cementing substantially the entire surface of each turned-back portion securely to the juxtaposed part, and means serving to waterproof the sheet material of the panel said end flap portions and said side flap portions when folded providing said display face portions with a smooth folded perimeter to minimize absorption of moisture by said display face portion when exposed to the weather.

2. A device of the class described formed of a sheet of non-metallic fibrous material, portions 15 of the sheet being folded back on the remainder of the sheet with the doubled over portions cemented together substantially throughout their superimposed area to form a substantially rigid panel of multiply thickness from edge to edge 20 and with the fold edges constituting a smooth perimeter of the panel to minimize absorption of moisture through the panel perimeter, all the cut edges of the sheet being spaced inwardly of the perimeter from the smooth fold edges, and at 25 least all but one of the cut edges being overlapped by the folded over portions to prevent absorption of moisture through the overlapped cut edges.

3. A panel formed from a piece of fibrous sheet material comprising a display face portion, flap 30 portions formed integrally with the display face portion adapted when folded back to cover the back face of said display face portion evenly throughout its area except for comparatively small spaces between the flaps, means cementing 35 the turned-back portions securely in the specified positions, and means serving to waterproof the sheet material of the panel.

4. A panel formed from a piece of fibrous sheet material comprising a display face portion, two 40 end flap portions formed integrally with the display face portion and adapted when folded back to cover the back surface of the display face portion, two side flap portions also formed integrally with the display portion and adapted when folded back to cover the back surfaces of said end flap portions, means cementing the turned-back portions securely in the specified positions, and means serving to waterproof the sheet material of the panel.

50 NORVAL F. WILSON.
